E. R. BURTNELL

INTERNAL COMBUSTION ENGINE

Filed May 21, 1925

FIG. 1.

Fig. 2.

Inventor: —
Everett R. Burnett
By Martin Smith atty.

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed May 21, 1925. Serial No. 31,804.

My invention relates generally to internal combustion engines, and more particularly a device for admitting a dilutent volume of residual gases or products of combustion 5 to the fresh fuel charge volume that is passing through the transfer duct from a pumping chamber to a combustion chamber in a multi-cylinder engine.

My co-pending patent application filed 10 Jan. 15, 1925, Ser. No. 2527 and application Ser. No. 20,117, filed Apr. 2, 1925 disclose multi-cylinder engines designed to operate on the two stroke cycle principle, and having charge volume transfer ducts leading 15 from the pumping chambers to the combustion chambers, and it is the principal object of my present invention to provide relatively simple and efficient means, preferably valve controlled, for admitting ducts, 20 in which velocity of flow of the fresh fuel charge volume is attained, a dilutent volume of products of combustion or residual gases, thereby insuring a highly effective mixture 25 of the dilutent volume with the fuel charge volume before the latter passes into the combustion chamber with the result that high combustion temperatures under high compression are overcome, and the undesirable action and results of pre-ignition 30 and detonation are prevented.

With the foregoing and other objects in view, my invention consists in certain novel features of construction and arrangement of parts that will be hereinafter more fully described and claimed and illustrated in the accompanying drawings in which:

Fig. 1 is an elevational view of a multi-cylinder engine and showing my improved dilutent volume admission means associated 40 with one of the fuel volume transfer ducts thereof.

Fig. 2 is a vertical section taken lengthwise through the center of my improved dilutent volume admission device.

Referring by numerals to the accompanying drawings, 10 designates a cylinder block, in which is formed a plurality of bores to form combustion chambers and certain of said bores have two diameters so as to provide charge volume pumping chambers, such as 11.

As more fully set forth in my above mentioned co-pending patent applications, a fuel

charge volume transfer duct, such as 13 leads from the upper portion of the pumping chamber 11 to the combustion chamber of another one of the two diameter cylinders and my improved dilutent volume admission device is directly connected to this duct intermediate its ends.

As illustrated, the device includes a short tubular member 14 that is fitted into and forms a part of duct 13 and positioned within this member is a Venturi tube 15.

Depending from tubular member 14 is a bracket 16, the lower end of which carries a short tubular member 17 that is parallel with member 14, and projecting from the inner end of this member 17 through bracket 16 and into the passageway through venturi member 14 is a jet tube 18.

Formed in the end of tube 17, directly opposite the lower end of this jet tube 18, is an opening that is normally closed by a plug 19, thus giving ready access to said jet tube, in the event of removed replacement or repairs.

Secured to the end of tube 17, opposite the end that is fitted with jet tube 18 and plug 19, is the upper end of a tubular fitting 20, having near its upper end, and inlet port 21, for the admission of the dilutent volume, such as residual gases or products of combustion.

A spring-held poppet valve 22 is adapted to rest on a seat 23, that is formed in the upper portion of tubular member 20 above inlet 21, and said valve is lifted from its seat by any suitable mechanical means, preferably a push rod, such as 24 that is actuated by means of a cam or eccentric 25.

The valve unseating means must necessarily be timed so as to open or unseat the valve, only during the period of fresh charge column movement through the transfer duct 13, toward the combustion chamber to which said duct leads. Obviously the valve 23 must be closed during the period of the suction or inlet stroke of the piston within the pumping chamber to which the transfer duct is connected.

Arranged for operation within tubular member 17 is a throttle valve 26, the shaft or axis of which is provided with a crank arm 27, and the latter being connected by a rod 28 or the like, to the lever that actuates

the throttle of the carburetor that supplies gaseous fuel mixture to the pumping chambers of the engine.

The connections between arm 27 and carburetor throttle actuating lever are such that the diluent volume throttle valve 26 is caused to open at a predetermined time in relation to the opening of said carburetor throttle valve.

10 As the engine with which my improved diluent volume admission device is associated, is operated, the opening of the carburetor throttle valve will, at certain period, open throttle valve 26.

15 On the inward movement of the piston within the pumping chamber from which duct 13 leads, a fresh fuel charge will be pumped or forced through said duct, and simultaneous with this action, poppet valve 22 is unseated to admit through port 21 and through the upper portion of member 20 and through tubular member 17, a diluent volume of residual gases or products of combustion.

20 25 The velocity of the flow of charge volume through duct 13 and particularly through the venturi restriction therein will produce an induction of the diluent volume through jet tube 18 from the chamber within tubular member 17, and this diluent volume will be thoroughly mixed with the charge volume as the latter passes into the combustion chamber. The bore of tube 18 and the venturi opening 15 should be properly calibrated in order to meter the proper proportion of diluent volume to the fuel charge volume.

30 35 During the suction stroke of the piston within the pumping chamber, valve 22 is

closed, thereby cutting off the inlet of diluent volume to the admission device and transfer duct.

A diluent volume admission device of my improved construction is comparatively simple, may be easily and cheaply produced, and is very effective in performing its intended functions.

It will be readily understood that minor changes in the size, form and construction of the various parts of my improved internal combustion engine may be made and substituted for those hereinafter shown and described without departing from the spirit of the invention, the scope of which is set forth in the appended claims.

I claim as my invention:

1. In combination with an internal combustion engine having a pumping chamber and a combustion chamber, a duct leading from said pumping chamber to said combustion chamber, said duct having a venturi restriction therein and means for admitting a diluent volume to said duct adjacent to said venturi restriction.

2. In combination with an internal combustion engine having a pumping chamber and a combustion chamber, a duct leading from said pumping chamber to said combustion chamber, said duct having a venturi restriction therein, means for admitting a diluent volume to said duct adjacent to said venturi restriction and valvular means associated with said admission means for controlling the passage of diluent volume therethrough.

In testimony whereof I affix my signature.
EVERETT R. BURTNETT.
